UNITED STATES PATENT OFFICE.

JULIUS I. WILE, OF CHICAGO, ILLINOIS.

DESIGN FOR A NEWSPAPER-HOLDER.

SPECIFICATION forming part of Design No. 32,761, dated May 29, 1900.

Application filed April 21, 1900. Serial No. 13,817. Term of patent 14 years.

To all whom it may concern:

Be it known that I, JULIUS I. WILE, a citizen of the United States, residing at Chicago, in the county of Cook and State of Illinois, have invented and produced a new and original Design for Newspaper-Holders, of which the following is a specification.

Referring to the accompanying drawings, which show said design, Figure 1 is a view in front perspective of a newspaper-holder of said new design, and Fig. 2 a view in side elevation thereof.

The leading feature of the design is that of a stem *a*, extending from any base *A* and branching to form the periphery *a'* of the newspaper-holder, said periphery comprising, as shown, oppositely-extending portions *b*, upwardly-extending portions *b'*, downwardly and outwardly inclined portions *b''*, changing to curves *b'''*, rearwardly-extending portions

b'''', changing to curves *b''''*, upwardly-converging portions *b''''*, changing to curves *b'''''*, and downwardly-converging portions *b''''''*, meeting in a common curved portion *b''''''*. Thus described the holder is composed of two symmetrical halves and has, as viewed from the front, somewhat the outline of a heart supported centrally of its base, but having recesses at its base on opposite sides of the supporting-stem and having also a blunt recessed apex. The back-forming portion of the holder is inclined rearwardly, as shown.

What I claim as new, and desire to secure by Letters Patent, is—

The design for a newspaper-holder, as shown and described.

JULIUS I. WILE.

In presence of—
D. W. LEE,
A. D. BACCI.
